DESIGN FOR A DRESS

Linda Iannicelli, New York, N. Y.

Application October 8, 1940, Serial No. 95,693

Term of patent 3½ years

To all whom it may concern:

Be it known that I, Linda Iannicelli, a citizen of the United States and a resident of the city of New York, in the county of Kings and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress shown in Fig. 1. The characteristic feature of my design resides in the combination on the dress disclosed of the specific embroidered pocket members in association with the embroidered belt member, as shown.

I claim:

The ornamental design for a dress, substantially as shown and described.

LINDA IANNICELLI.
